METHOD AND MEANS FOR RECEIVING WIRELESS WAVES

Application filed April 27, 1927, Serial No. 186,881, and in Germany February 12, 1924.

Application filed in Germany February 12, 1924.

This invention relates to a wireless receiver and more particularly to receivers of the regeneratively coupled type.

In the operation of very sensitive receiver arrangements, it is necessary to use regeneratively coupled thermionic tubes. It is therefore, customary to bring the energy picked up by the aerial and fed to a triode to act again upon the grid circuit of the first amplifier or one of the following amplifier tubes, in order to insure repeated amplification by one and the same amplifier set. Now, arrangements of this kind involve the disadvantage that, if the permissible back-coupling is but slightly exceeded, oscillation of the device is occasioned, with the result that energy is supplied to the antenna and is radiated off by the latter. Such radiation results in marked disturbance in the neighborhood of the receiver outfit.

It is an object of this invention to prevent such radiation.

Now, according to the disclosures of the present invention, this drawback is obviated by the arrangement shown in the drawing, wherein the circuit diagram of a regeneratively coupled receiver is shown embodying my invention.

In the figure, a regeneratively coupled thermionic tube is shown intentionally adjusted so that oscillations are produced, by back-coupling between coils 2 and 3. Now, incoming energy is fed to the antenna 4 and thence supplied to the grid circuit of a detector tube 19, the detecting action being insured in well-known manner by means of a grid condenser 6 and a leak 7. Inserted in the plate circuit of the detector tube is a resistance 9 which, for example, may also be directly connected to the grid 10 of a triode 1.

The grid of the triode 1, on the one hand, will be negatively charged owing to the action of the stopper condenser 11, while, on the other hand, it will become positively charged upon each diminution of the plate current in the audion tube 19. The mean direct current potential which prevails at the grid 10,

therefore changes upon each change of the current in the plate circuit of the detector tube.

Each change in the grid potential, however, results in the creation of an oscillation in the plate circuit of triode 1. These oscillations have an amplified energy, compared with the incoming oscillations so that they can be rendered perceptible directly by the aid of a rectifier or else they are fed to additional amplifier stages. What is essential in the scheme is that the frequency of the oscillations produced by the triode 1 in accordance with the direct current variations in the plate circuit of the detector tube 19 may be chosen at will, for instance, it may be considerably lower than the incoming frequency.

In this manner, additional amplifier stages may be effectively employed. A telephone, for example, is inserted either in the plate circuit of triode 1, say, in series with the battery, or in one of the following amplifier or audion circuits. The advantage offered by the scheme is that no reaction upon the antenna can be produced by the oscillations occurring in circuit 3. This is true because the antenna circuit is tuned to a different frequency than that at which the oscillator 1 is oscillating and hence the tuned antenna circuit offers an extremely high impedance

to any currents which would tend to be radiated by virtue of the generation of oscillations in the oscillator 1. By making the oscillator 1 oscillate at a relatively low frequency such as 50 kilocycles the possibility of radiation will be still lessened by virtue of the choice of such a low frequency.

The essential and basic feature of the invention as shown by way of example by the embodiment given in the drawing is capable of a great number of modified circuit arrangements, as will be seen. It includes the following: A local oscillator or wave-generator of any desired frequency is placed in such a dependency upon the incoming energy changed by a thermionic relay, that each change in the current of the plate circuit of said relay results in the production of a local wave train; though this does not persist. Indeed, it lasts only until the impulse

caused by the instantaneous incoming current has acted. Hence, no permanent production of oscillations is possible.

As a technical means to carry this idea into effect, there may be mentioned, by way of example, a method of governing the grid direct current potential of a local oscillator by two coacting causes or actions, namely, an oscillation-impeding action by locally 10 generated oscillations, and an oscillation releasing action by the incoming currents.

The means adapted to prevent the arising of constant local oscillations consists of the condenser 11 connected in the grid circuit of triode 1. The grid 10, as a consequence, has such a negative charge that local oscillations are not produced. The plate current of the thermionic tube 19, which flows through the resistance 9, also sets up a negative potential 20 at the grid 10. However, when the current through the resistance 9 is subject to changes, for instance, when the same diminishes, (and this will always happen upon the arising of the audion effect), the voltage 25 fall across resistance 9, and consequently the negative charge of the grid 10, decreases. When this happens, local oscillations can be produced at once, and these persist until the plate current of 19 again changes. The 30 circuit arrangement hereinbefore described is suited both for the reception of wireless telegraphy signals as well as for wireless telephony work.

It is, of course, possible to provide between 35 antenna 4 and tube 1 a plurality of radio frequency amplifier and audion circuit connections instead of only one audion arrangement. As to the rest, it may be mentioned that, so far as potential balance is concerned, 40 the only point of importance is that a stationary state of balance is obtained at such a mean direct current potential that the tube just fails to oscillate constantly, and that, upon this balance being disturbed, the original condition is spontaneously restored. At 45 any rate, every transient disturbance in the mean grid potential will be followed by the production of oscillations in circuit 3, and this is the essential feature of the invention.

50 The operation of the system as shown in the drawing may be explained as follows. At the time of zero reception, that is, when no signals are being received there is a certain constant current flowing in the plate circuit 55 of audion tube 19. This produces a certain voltage drop across the plate impedance of resistance 9 of tube 19. Grid 10 of tube 1 is connected to the impedance 9 at a point such that relative to the filament of tube 1 it is maintained at a potential which prevents 60 oscillation generation in tube 1. This bias is by virtue of condenser 11 maintained notwithstanding the fact that there is a feed back arrangement for tube 1 namely, tuned 65 circuit 3 and coupling 2.

When an incoming wave causes a drop in current through tube 19, the negative bias on 70 10 is lessened, allowing of oscillation generation. The resulting output of tube 1 as shown is amplified, detected, reamplified and 75 is finally made apparent by virtue of a loud-speaker or phones connected to the audio frequency amplifier, shown between the detector and phones.

Having thus described my invention, what 80 I claim is:

1. In a radio receiving apparatus adapted for the reception and transformation of electromagnetic waves into sound, a local oscillator, means connected to the grid and filament 85 of said oscillator to prevent oscillation, and means responsive to incoming waves for counteracting said oscillation preventing means allowing said local oscillator to oscillate.

2. In radio receiving apparatus an antenna; a detector, means for coupling said antenna to the detector; a resistance in the output circuit of said detector; an oscillator tube; said resistance being connected across the input circuit of said oscillator in such a manner that the normal plate current of said detector through said resistance maintains the grid of said oscillator at a negative potential 90 unsuited for oscillation generation.

3. A method of operating a regeneratively coupled receiving circuit without radiation which consists in collecting signal energy of a desired frequency, rectifying said energy, producing local oscillations of a frequency 100 other than said signal frequency, modulating said local oscillations with said rectified signal energy, suppressing said local oscillations during periods when signal energy is not collected, and, finally detecting and utilizing said modulated local oscillations.

4. A method of reception which consists in collecting signal energy of a desired frequency, producing local oscillations of a different frequency, rectifying said signal energy, modulating said local oscillations with said rectified signal energy; and controlling the production of said local oscillations in such a manner that local oscillations are produced only when signal energy is collected.

SIEGMUND LOEWE.
